UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

ALL-METAL DOOR CONSTRUCTION.

Application filed November 10, 1924. Serial No. 749,017.

This invention relates generally to doors and refers more particularly to metal doors that are designed for use with vehicle bodies of the closed type.

One of the essential objects of the invention is to provide a light and durable door of this type that is constructed entirely of metal and is provided with an exceptionally strong and rigid frame which will prevent the door from weaving and twisting or otherwise weakening while in use.

Another object is to provide the frame of the door with simple and effective means for preventing the vertically movable window panel from wobbling or moving transversely of the door frame when in lowered position.

Further object is to provide a neat and attractive door that is simple in construction and can be manufactured at a comparatively low cost.

With the above and other objects in view the invention consists in certain novel features of construction, combinations and arrangements of parts as will be more fully described and particularly pointed out in the appended claims.

In the accompanying drawing;

Figure 1 is a rear elevation of a door embodying my invention.

Figure 2 is a horizontal sectional view taken on the line 2—2 of Figure 1.

Figure 3 is a vertical sectional view taken on the line 3—3 of Figure 1.

Figure 4 is a horizontal sectional view taken on the line 4—4 of Figure 1.

Figure 5 is a section view taken on the line 5—5 of Figure 1.

Referring now to the drawing in which like characters of reference designate corresponding parts throughout the several views, the numeral 1 designates a door embodying my invention having a frame 2 that is preferably constructed of sheet metal. As shown, the frame preferably comprises the spaced upright members 4 and 5 respectively and the top and bottom cross members 6 and 7 respectively. To provide a strong and durable construction, the upright members 4 and 5 are preferably channel-shape in cross section and are provided at the outer edges thereof with the laterally extending flanges 8 and 9 respectively, while the top and bottom

cross members 6 and 7 respectively are also preferably channel-shape in cross section and are provided at the lower outer edges thereof with depending flanges 10 and 11 respectively. To provide a rigid connection, the top and bottom members 6 and 7 respectively are preferably welded to the upright members 4 and 5 respectively and are reinforced by a sheet metal panel 12 that conforms to the shape of the frame 2 and constitutes the front exterior finish of the door. As shown, this panel is preferably provided at its bottom and side edges with return-bent flanges 13 and 14 respectively that are welded to the lateral flanges 8 of the upright members and to the depending flange 11 of the bottom cross member 7. The panel 12 is also preferably provided at its upper edge with a rearwardly projecting flange 15 that is welded to the upper face of the top cross member 6.

In the upper portion of the panel 12 is a relatively large opening 16 that is adapted to be closed by a suitable window 17. At the upper edge of this opening 16 is an inwardly extending flange 18 that preferably constitutes the window header finish strip and is preferably provided at its inner edge with a vertical off-set portion 19 that is welded to the depending flange 10 and to the lower face 20 of the top cross member 6 of the door frame. At the lower edge of the opening 16 is an inwardly extending flange 21 that constitutes the window sill and is preferably return-bent intermediate its ends to provide a depending flange 22 to which a suitable rubber weather strip 23 is preferably secured for engagement with the outer face of the window 17. At the side edges of the opening 16 are a pair of substantially parallel inwardly extending flanges 24 that are preferably off-set laterally and are welded to the flanges 9 and to the inner faces of the upright members 4 and 5 respectively. Thus, portions of the panel 12 cooperate with the channel-shaped upright members 4 and 5 respectively and the channel-shaped top cross member 6 to provide hollow box-like frame members which are extremely strong and durable and will prevent the door from weaving or twisting while in use.

The window 17 is preferably a sashless

glass panel that is adapted to be raised or lowered in the door frame 2 by means of suitable control mechanism designated generally by the numeral 25. For receiving the glass panel 17 when it is raised, I preferably provide an inverted substantially U-shaped frame 26 that is secured to the top cross member 6 and upright members 4 and 5 respectively of the door. As shown, a 10 channel shaped strip 27, preferably of resilient material, is preferably secured to the header portion 28 of the frame 26 for receiving the upper edges of the glass panel 17 when raised, while similar channel strips 15 29 are preferably secured to the upright members 30 of the window frame 26 and are adapted to guide the glass panel 17 during the raising and lowering movement thereof. To prevent the window panel 17 from wab- 20 bling or moving transversely of the door frame when in lowered position, portions of the strips 29 preferably extend below the window frame 26 and bear against laterally extending flanges 30' of the channel-shaped 25 upright members 4 and 5 respectively as shown in Figure 4 of the drawing.

For reinforcing the door intermediate its ends, I preferably provide a channel-shaped metal board 31 that is secured at the opposite 30 ends thereof to the upright members 4 and 5 respectively of the door frame adjacent to the belt finish strip 32 connecting the upright members 30 of the window frame 26. As shown, this board 31 preferably supports 35 a suitable lock (not shown) for the door as well as all of the window control mechanism 25, and is preferably welded to the upright members 4 and 5 respectively of the door frame to insure a rigid connection thereof.

40 To provide a neat interior finish, the door is preferably provided with suitable trimming material 33 which is preferably attached to the door frame 2 by means of suitable snap fasteners 34 that engage suitable 45 openings 35 which are spaced the proper distance apart in the door frame.

From the foregoing description it will be readily apparent that I have provided an all metal door in which every bit of wood has 50 been eliminated. Thus, the door may be subjected to intense heat necessary in applying enamel or paint finish without affecting the structure. Moreover, the window regulator arm 36 cooperates with the flanges 30' 55 for guiding the window panel and preventing the same from swaying inwardly, for instance when the door is jarred.

60 While it is believed that from the foregoing description the nature and advantages of the invention will be readily apparent, I desire to have it understood that I do not limit myself to what is herein shown and described, and that such changes may be re-

sorted to when desired as fall within the scope of what is claimed.

What I claim as my invention is:

1. A door for vehicle bodies comprising a sheet metal panel having an area substantially equal to the area of the door and having a window opening therein at the upper end thereof, and a reinforcing and supporting frame for said panel including two spaced pillars and three spaced cross members, said pillars extending longitudinally of the panel at the side edges thereof and at the sides of the window opening, one of said pillars being shorter than the other and having one end terminating short of an end of said panel, two of said cross members extending between and terminally secured to said pillars, and the other of said cross members being secured to and serving as a continuation of the shorter of the two pillars and having portions secured to said panel and to the other of said pillars at points beyond an end of said short pillars whereby a portion of said last mentioned cross member constitutes an extension or continuation of said short pillar for the longitudinal reinforcement of said panel and door.

2. A door for vehicle bodies comprising a sheet metal panel having an area substantially equal to the area of the door, and a reinforcing and supporting frame for said panel including two laterally spaced pillars 95 and three vertically spaced cross members, one of said pillars being substantially equal in length to the length of said panel and extending longitudinally thereof at one side edge thereof, the other of said pillars 100 extending longitudinally of said panel at the other side edge thereof and having its upper end at the upper end of the panel but having its lower end terminating an appreciable distance shorter of the lower end 105 of said panel whereby the lower end of said last mentioned pillar is disposed in stepped relation to the lower end of the first mentioned pillar, one of said cross members extending between and secured to said pillars 110 at the upper ends thereof, the other two of said cross members being substantially L-shaped and arranged with the legs of the L's 115 extending longitudinally of the second mentioned pillar and terminating a short distance apart so as to serve as gussets for strengthening and reinforcing said short pillar, the lowermost of said L-shaped cross members serving as a depending continuation of said second mentioned pillar and 120 having portions secured to said panel at the lower end thereof and to the first mentioned pillar.

In testimony whereof I affix my signature.

WILLIAM MARSHALL.
